UNITED STATES PATENT OFFICE.

MATYAS CZINER, OF NEW YORK, N. Y.

LAMP.

SPECIFICATION forming part of Letters Patent No. 251,702, dated January 3, 1882.

Application filed April 25, 1881. (No model.)

To all whom it may concern:

Be it known that I, MATYAS CZINER, a citizen of the United States of America, resident of the city, county, and State of New York, have invented certain new and useful Improvements in Lamps, which improvements are fully set forth in the following specification, reference being had to the accompanying drawings, in which—

10 Figure I is a vertical section of a lamp embodying my invention, and Fig. II is a vertical section of the burner.

Similar letters indicate corresponding parts.

15 My invention relates to that class of reservoir-lamps in which the oil-supply chamber is, by means of a continuous siphon action, also by the operation of a float-valve, rendered independent of the main reservoir as to the level of oil in the latter.

20 The object of my improvements is to construct a lamp-body such as will admit, in proportion to the size of its feed-receptacle, any desired number of arms and burners, shall be applicable to chandelier, bracket, or table, and, 25 owing to its peculiar form, size, and compactness, shall be especially adapted for use in articles of ornament, bijoutry, statuettes, figures, signs, &c.

Safety from explosion is ordinarily sought to 30 be attained by preventing the accumulation of oil in the vicinity of the flame. I, however, while more perfectly isolating the oil and its vapors from places of ignition, seek to insure greater safety by the process of refining the 35 oil previous to its entering the supply-chamber, said process being carried on in the reservoir of the lamp-body itself.

In the drawings, the letter A designates the 40 spherical lamp-body, having an opening, a, closed by a screw-plug, for the admission of oil, and containing, compactly arranged, the shaft B, fastened to the main body at both its ends; and within said shaft the supply-tube D, which latter has floating valve E E, and is connected 45 with the reservoir by siphon N.

R R is a perforated partition or false bottom 46 upholding the metallic filter and refiner S, composed of pulverized and well-mixed asbestos, carbonized serpentine rock, and bone-black.

50 The secondary parts, outside of the spherical reservoir—to wit, neck C, feed-pipe G, feed-re-

ceptacle F, arm or arms H, and pedestal P—need no special description.

I is the burner containing the air-pipe K, encompassed by a mineral cone, serving for an 55 "everlasting wick," said cone being formed of asbestos and soapstone, first treated with coal-tar and ammoniacal liquor, then molded, and lastly baked and made to fit tightly the sides of the burner.

M is the outer case of the mineral cone or wick, is made of metal, and has an internal 60 perforated flange, T, to catch the solid impurities of the flame, said impurities being consumed thereon by the intense heat to which 65 they are exposed. This conic frustum is movably attached to the burner I, to which it is similar in form, and admits of a vertical sliding on said burner, so that by drawing it up or down the volume of flame may be respectively contracted or enlarged at will.

O is the terminal portion of arm H, one-fourth of an inch in diameter.

The operation is as follows: The oil filling 75 the reservoir, after becoming purified and refined by percolation through the metallic filter S, is taken up from the bottom of the reservoir by siphon N rising, wherein, under hydrostatic pressure to the top of the supply-tube D, it descends into said tube until the float-valve, rising 80 with the liquid, closes the opening b, preventing thereby the further entrance of the oil. When, however, owing to the consumption of oil by the burners, the level of the liquid in the supply-tube D is lowered, the float, descending 85 with the falling liquid, uncovers the opening for renewed supply of oil, until the reservoir A is entirely exhausted. The final passage of the oil through G, F, and H into I and its final consumption at the points of the mineral cone 90 require no explanation.

I claim and desire to obtain Letters Patent for—

1. The combination, with the lamp-body, of an interior closed chamber connected with the 95 body by a siphon having its inner end closed or opened by a ball-valve, substantially as described.

2. The combination of the external chamber or reservoir, the interior or supply chamber, and a siphon connecting with substantially the 100 lowest part of the reservoir and the top of the

closed supply-chamber, whereby feeding of the oil will be uninterrupted at its highest and lowest level and undue accumulation of oil at the burner is prevented, substantially as described.

5 3. The combination of the lamp body having the shaft B with the supply-chamber and the siphon.

4. The burner I, containing the air-pipe K, surrounded by a mineral cone serving as a wick, substantially as set forth.

5. The combination, with the burner, of the conic frustum M, having an internal perforated flange to catch the solid impurities of the flame and capable of sliding vertically upon the burner, substantially as and for the purpose specified.

6. The combination, in a lamp-body, of the chamber for the unfiltered oil above, the filtering device R S, and a chamber for refined and filtered oil below, substantially as described. 20

7. The combination of the burner having the mineral cone described, the tube H, the supply-chamber D, the siphon, and the reservoir, all as set forth.

In testimony that I claim the foregoing as 25 my own I have hereto affixed my signature in presence of two witnesses.

MATYAS CZINER.
